CLAIM

The ornamental design for a container for storing a product, as shown and described.

DESCRIPTION

FIG. 1 is a top front perspective view of a container for storing a product, according to one embodiment of the present disclosure, the container having a base member and a cover member;

FIG. 2 is a top rear perspective view of the container shown in FIG. 1;

FIG. 3 is a top plan view of the container shown in FIG. 1;

FIG. 4 is a bottom plan view of the container shown in FIG. 1;

FIG. 5 is a side elevation view of the container shown in FIG. 1;

FIG. 6 is another side elevation view, opposite the view shown in FIG. 5, of the container shown in FIG. 1;

FIG. 7 is an end view of the container shown in FIG. 1, the container being flipped as compared to the view shown in FIG. 1;

FIG. 8 is another end view, opposite the view shown in FIG. 7, of the container shown in FIG. 1;

FIG. 9 is an exploded top front perspective view of the container shown in FIG. 1;

FIG. 10 is an exploded top rear perspective view of the container shown in FIG. 1;

FIG. 11 is a top front perspective view of a container for storing a product, according to an alternative embodiment of the present disclosure, the container having a base member and a cover member;

FIG. 12 is a top rear perspective view of the container shown in FIG. 11;

FIG. 13 is a top plan view of the container shown in FIG. 11;

FIG. 14 is a bottom plan view of the container shown in FIG. 11;

FIG. 15 is a side elevation view of the container shown in FIG. 11;

FIG. 16 is another side elevation view, opposite the view shown in FIG. 15, of the container shown in FIG. 11;

FIG. 17 is an end view of the container shown in FIG. 11, the container being flipped as compared to the view shown in FIG. 11;

FIG. 18 is another end view, opposite the view shown in FIG. 17, of the container shown in FIG. 11;

FIG. 19 is an exploded top front perspective view of the container shown in FIG. 11;

FIG. 20 is an exploded top rear perspective view of the container shown in FIG. 11;

FIG. 21 is a top front perspective view of a container for storing a product, according to yet another alternative embodiment of the present disclosure, the container having a base member and a cover member;

FIG. 22 is a top rear perspective view of the container shown in FIG. 21;

FIG. 23 is a top plan view of the container shown in FIG. 21;

FIG. 24 is a bottom plan view of the container shown in FIG. 21;

FIG. 25 is a side elevation view of the container shown in FIG. 21;

FIG. 26 is another side elevation view, opposite the view shown in FIG. 25, of the container shown in FIG. 21;

FIG. 27 is an end view of the container shown in FIG. 21, the container being flipped as compared to the view shown in FIG. 21;

FIG. 28 is another end view, opposite the view shown in FIG. 27, of the container shown in FIG. 21;

FIG. 29 is an exploded top front perspective view of the container shown in FIG. 21; and,

FIG. 30 is an exploded top rear perspective view of the container shown in FIG. 21.
